J. D. HEATER,
SHIELD FOR VESTIBULE CURTAINS,
APPLICATION FILED OCT. 3, 1914.

1,169,814.

Patented Feb. 1, 1916.

UNITED STATES PATENT OFFICE.

JACOB D. HEATER, OF DAYTON, OHIO, ASSIGNOR TO THE BARNEY AND SMITH CAR COMPANY, OF DAYTON, OHIO, A CORPORATION OF WEST VIRGINIA.

SHIELD FOR VESTIBULE-CURTAINS.

1,169,814.

Specification of Letters Patent.

Patented Feb. 1, 1916.

Application filed October 3, 1914. Serial No. 864,725.

To all whom it may concern:

Be it known that I, JACOB D. HEATER, a citizen of the United States, residing at Dayton, in the county of Montgomery and State of Ohio, have invented certain new and useful Improvements in Shields for Vestible-Curtains, of which the following is a specification, reference being had therein to the accompanying drawing.

10 This invention relates to shields for vestibule curtains. Vestibule curtains are commonly employed to bridge the space between the ends of the vestibules of two adjacent cars and to form side walls for the passage-15 way leading from one car to the other. The vestibule curtain is mounted on a vertically arranged spring roller, of ordinary construction, on one vestibule and is drawn across the space between the two vestibules 20 and made fast on the other vestibule. It is desirable that the curtain roller be inclosed in a casing or shield, both to protect the roller and curtain and to render the structure more sightly. Ordinarily, these 25 shields or casings entirely inclose the curtain roller except for a slot through which the curtain is drawn, and are secured to the supporting structure by means of rivets or bolts. When it is desired to have access to 30 the roller to make repairs or for any other purpose, it is necessary to remove these bolts or rivets in order to move the casing away from the roller. It has been attempted to provide a hinged door for the casing, but 35 the construction is objectionable.

The object of the present invention is to provide a shield having a movable side wall pivotally supported to permit the same to be swung into either of two positions, one 40 of which will close the casing about the curtain roller, with the exception of the slot for the curtain, and the other of which will open this casing to permit access to the curtain roller and to so construct the device that 45 when in its open position the movable wall will be within the casing; and further, to provide means to positively hold the movable wall in either of said two positions.

It is also an object of the invention to

provide such a device of a very simple, durable construction which will have no parts easily broken or disarranged in service.

In the accompanying drawings Figure 1 is a sectional view taken lengthwise of the end portions of the vestibules of the two cars, partially broken away, showing the invention applied thereto; Fig. 2 is a transverse sectional view of a shield taken just inside of the top plate; and Fig. 3 is a plan view of the shield.

In these drawings I have illustrated one embodiment of my invention and have shown the same as applied to a car vestibule of ordinary construction. In this particular vestibule the curtain is mounted on a part of the vestibule frame, such as one of the vestibule posts. As here shown, this post comprises two vertical members arranged at right angles one to the other, and I have utilized these members of the post to form two of the fixed walls of the shield. It will be understood, however, that in case the vestibule post is of a different construction, or it is not desirable to utilize the same in this manner, the fixed walls of the casing may be of any suitable construction and mounted in any suitable manner.

In this particular illustration of the invention I have shown the vestibule curtain mounted upon a roller 2 which may be a spring roller of ordinary construction, and have shown the roller as mounted in brackets 3 to permit it to rotate about a vertical axis. These brackets are mounted upon the frame of the vestibule, and, in the present instance, on the vestibule post. As above explained, this post comprises an angle iron, the two parts of which are shown at 4 and 5. Rigidly secured to the vestibule post, above the upper bracket 3, is a top plate 6, preferably provided with upwardly extending flanges 7, by means of which it is secured to the parts 4 and 5 of the post. A bottom plate 8 of similar construction is secured to the vestibule post beneath the lower bracket 3. As has been stated, the members 4 and 5 of the vestibule post form two of the fixed walls of the casing. A third fixed wall is

arranged parallel with the member 4 of the post, but is of a less width than that post. In the present instance this third side wall is shown at 9 and consists of an angular member having one flange rigidly secured to the part 5 of the post. The outer edge of this side wall terminates some distance back of the outer edge of the part or flange 4 of the post, thus providing an open space between these walls somewhat greater in length than the width of the casing. A movable wall 10 is provided to close this space. Preferably, this wall is curved about a vertical axis so as to provide a rounding front to the casing when the movable wall, or closure, is in its closed position. The movable wall is preferably mounted on a vertical axis, and to this end it is secured at its upper and lower edges to two sector shaped arms 11, which in turn are mounted on pivot pins 12 in the top and bottom plates 6 and 8. Preferably, the forward movement of the closure or movable wall is so limited that when it is in its extreme forward position a slot 13 will be provided between the forward edge thereof and the edge of the flange 4 of the post, to permit the passage of the curtain. To so limit the movement of the closure I have projected the rear edge of the closure outwardly from the arc of the circle about which the remainder of the closure is described. This lengthens the radius of the rear edge of the closure and causes the same to engage the forward edge of the fixed side wall 9, and thus check the forward movement of the closure and form a dust tight joint at that point. This increased radius may be secured by the lengthening of the inner edges of the arms 11, by folding or rolling the rear edge of the plate which forms the closure, or in any other suitable manner. In the present instance I have employed both of the methods above mentioned, that is, I have lengthened the rear edges of the arms and have folded the plate upon itself, but it will be understood that either of these methods may be used without the other with satisfactory results. It will be noted that the curved swinging wall having its rear edge arranged to co-operate with the straight side wall of the housing provides a construction which will not be choked up or hampered by the entrance of cinders or dust into the joint. If any cinders lodge in the joint while the closure is in its extended position they will be immediately released when it begins its rearward movement. Means are provided to hold the rear edge of the closure against the side wall of the housing and thus maintain a tight joint. In the present instance, this means is of such a character that it will hold the closure either in its open or its closed position. As here shown, this means com-

prises a spring catch in the form of a flat spring 14 secured on the upper surface of the top plate 6 and having a pin 15 extending through a hole in the top plate and adapted to extend in front of the upper arm 11 when the closure is in its open position, and to extend through an opening 16 in said arm when the closure is in its closed position. This particular type of catch is of special value in connection with a device of this kind because it has no cavities or recesses of any kind in which cinders or dust may collect and thus interfere with the operation thereof.

The operation of the device will be readily understood from the foregoing description, and it will be apparent that I have provided a shield for the curtain roller which fits snugly in the angle of the vestibule post and which has a smooth finish which harmonizes with the structure of the vestibule. Further, it will be apparent that the device is provided with a large opening which can be readily opened and closed to permit of access to the roller or to entirely inclose the roller, and it will be apparent that the device is extremely simple in its construction and of a very strong, durable character, and is not likely to be broken or disarranged in service.

While I have shown and described one embodiment of my invention, I wish it to be understood that I do not care to be limited to the details of construction shown and described, for obvious modifications will occur to a person skilled in the art.

Having thus fully described my invention, what I claim as new and desire to protect by Letters Patent, is:

1. A shield for a curtain roller comprising a housing having walls within which said roller is mounted, the adjacent edges of two of said walls being spaced apart, said housing also having a wall mounted on an axis and adapted to be moved into and out of the space between said edges, one portion of said last-mentioned wall having a radius slightly greater than the distance between said axis and one of the said adjacent edges, and the remaining portion of said wall having a radius slightly less than that distance, whereby said first portion of said wall will engage the last-mentioned adjacent edge to limit the movement of said wall and to form a tight joint at the engaging portions.

2. A shield for a curtain roller comprising a housing having walls, the adjacent edges of two of said walls being spaced apart, said housing also having a closure comprising a plate mounted for swinging movement about an axis to enable it to be moved across the space between said adjacent edges, the radius of the rear edge of

said plate being of greater length than the radius of the forward portion thereof and being so arranged with relation to one of said adjacent edges that when said plate is 5 in its extended position said rear edge thereof will engage said last-mentioned adjacent edge and form a tight joint.

In testimony whereof I affix my signature in presence of two witnesses.

JACOB D. HEATER.
